DESIGN FOR A COOKING APPLIANCE OR THE LIKE

Kenneth L. Woodman, Mansfield, Ohio, assignor to Westinghouse Electric & Manufacturing Company, a corporation of Pennsylvania

Application January 10, 1940, Serial No. 89,369

Term of patent 14 years

To all whom it may concern:

Be it known that I, Kenneth L. Woodman, a citizen of the United States, residing at Mansfield, in the county of Richland and State of Ohio, have invented a new, original, and ornamental Design for a Cooking Appliance or the like, of which the following is a specification, reference being had to the accompanying drawing, forming a part thereof.

The figure is a perspective view of a cooking appliance showing my new design.

I claim:

The ornamental design for a cooking appliance or the like, substantially as shown and described.

KENNETH L. WOODMAN,
